PAPER CUTTER

Robert J. Matthews, Hasbrouck Heights, N. J.

Application October 10, 1944, Serial No. 558,064

4 Claims. (Cl. 164—61)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention is in paper machines and particularly is a paper cutting device.

The principal object of the invention is to provide novel means for forming a plurality of parallel slits in cardboard or paper blanks, leaving a predetermined portion of the blanks uncut.

Certain arts, as cryptography, require the use of large numbers of narrow strips of paper, cardboard, plastic or the like with printed data thereon. Normally, such strips are prepared in sets, and information on one strip of a set commonly bears an important relation to the information on other strips of the set. It is, therefore, necessary that great care be exercised to assure that all sets of such strips are complete without duplications or omissions. If such strips can be prepared and carried or shipped as sheets rather than separately, it is possible not only to effect economies in preparation for shipment but also to provide an easy check on the completeness of the sets.

The present invention contemplates the preparation of strips as indicated from blanks somewhat longer than the strips themselves require, the blanks being left unslit at one or both of their ends, it being intended then that the ultimate user of the strips separate them from the sheets.

Other objects will be apparent from a reading of the following description and claims.

In the drawings:

Figure 1 is an elevation of the invention showing only the principal elements thereof.

Figure 2 is an isometric sketch illustrating the organization of the parts of the invention.

Referring to the drawings, 10 represents a table over which the paper blanks are fed. Guides, as 10' and 10'', are provided to assist in the delivery of the blanks. The table surface is broken transversely at one point, as at 11. Just below the opening in table 10 is mounted for rotation a roller 12, so arranged that its periphery is tangent with or slightly above the upper surface of table 10. In the apparatus illustrated this roller is adapted for clockwise rotation.

At the right end of table 10 are arranged two other rollers, 13 and 14. These are serrated, and their notches or teeth fitted together. The rollers 13 and 14 rotate in opposite directions, 13 clockwise and 14 counterclockwise.

The roller 13 is mounted on a shaft, 15, and

2

mounted on opposite ends of the same shaft for rotation independent of roller 13 are cams 16 and 17. Cam 16 has a toe or extension, 16', and 17, a similar extension, 17'. In the preferred embodiment of the invention, cams 16 and 17 do not revolve through a full circle but oscillate through arcs determined by the requirements of the particular cutting operation to be performed.

The rollers 12 and 13 are driven in any desired fashion; this not forming a part of the present invention. Roller 14 turns with a shaft, 14', on one end of which is a gear wheel, 18 meshing with a gear wheel, 19, on the end of shaft 15. According to the drawings, both rollers turn at the same speed, but one may be driven at a higher rate, if desired, merely by varying the sizes of gears 18 and 19.

Just forward of roller 12 (to the right in Figure 2) is a shaft, 20, which may be mounted in any desired fashion, and this shaft carries cams 21 and 22, having toes 21' and 22' respectively. Mounted to ride on cams 21 and 22 are braking means 24 and 25, and these are adapted to extend upwardly through guides, as 26, and through table 10. Brake 24 has a flange, 28, fixed thereon, and this flange is adapted to compress a spring, 29, whenever the braking member is raised. Braking member 25 is similarly arranged. Shaft 20 may be driven through suitable gearing by the same means which drives the roller 12 and shaft 15 and in turn, by means of connecting rod 30 and eccentric 31, provides cam 16 with its oscillatory motion.

Means, as springs 40 and 41, are provided for holding the rollers 13 and 14 normally in engagement with each other.

The device operates in the following manner: Paper blanks are fed one at a time from any convenient type of hopper (not shown) to the table 10 and over the roller 12. The orientation of cams 21 and 22, with relation to 16 and 17, is such that, when the feeding operation occurs, braking means 24 and 25 will have been driven to their raised positions by the toes 21' and 22' of the cams 21 and 22. The braking means serve not only to restrain a blank until an earlier cutting operation has been completed but also to align a blank properly upon table 10 before entry into the cutters.

After a predetermined time interval, limited by the effective length of the cam projections 21' and 22', braking means 24 and 25 drop through table 10, and the paper blank is projected forwardly by the roller 12 and enters between rollers 13 and 14 where it is cut into strips by the inter-

acting rotating teeth thereof. Again, after a predetermined time interval, normally before the blank has passed completely through the cutters, cams 16 and 17, moving counterclockwise on shaft 15 under the influence of shaft 20 and linkage 30-31, will turn sufficiently for their toe members 16' and 17' to abut against roller 14 and thus disengage roller 14 from roller 13. The clearance provided between the cutters under these conditions is small, and gear wheels 18 and 19 are not disengaged. The blank will be propelled forwardly by roller 13 until it clears the machine, at which time cams 16 and 17 will move clockwise, rollers 13 and 14 will be re-engaged by springs 40 and 41, and the operation can be repeated.

Obviously, by properly relating the several cams, the sizes of their peripheral projections and their speeds of movement, it is possible to achieve any desired relation between the cut and the uncut portions of the paper blank.

The above description is in specific terms. It should be understood that the invention is not limited to the exact structure shown and described, and for the true scope of the invention reference should be had to the appended claims.

I claim:

1. In a machine for cutting a blank, a table or the like over which the blank is moved to be cut, a roller having a plurality of annular cutting edges, a second roller having a plurality of cutting edges adapted to cooperate with the cutting edges of the first mentioned roller to perform a cutting operation, means for feeding a blank over said table and between said rollers, means in the nature of a cam having a peripheral extension on one of said rollers for abutting against the other of said rollers to separate the two said last mentioned means being mounted for rotation independent of its roller, braking means including stops adapted to be projected through said table adjacent said rollers when said rollers are separated for preventing said feeding means from feeding a blank therebetween, and means connecting said braking means and the camming means to provide an oscillatory motion for the latter.

2. In a machine for cutting a blank, a rotatably driven roller having a plurality of annular cutting edges, a second rotatably driven roller having a plurality of cutting edges adapted to cooperate with the cutting edges of the first roller to perform a cutting operation, a table adjacent said rollers, means on said table for feeding a blank between said rollers, a shaft beneath said

table, means for rotating said shaft, a cam on said shaft mounted for rotation therewith, means operated by said cam for intermittently preventing said feeding means from feeding a blank on said table between said rollers, another cam independently rotatable on the end of one of said rollers and in contact with the other of said rollers, and means connecting said shaft and said last mentioned cam to provide for said last mentioned cam an oscillatory motion in response to the rotation of said shaft.

3. In a machine for cutting a blank, a first roller having a plurality of annular cutting edges, a second roller having a plurality of annular cutting edges adapted to cooperate with the annular edges of the first mentioned roller said second mentioned roller being in superposed relation to said first mentioned roller and being driven thereby, said first mentioned roller having a cam at each end thereof mounted for independent rotation with respect thereto each cam having an extension adapted to abut against the second mentioned roller to lift the same when in one position, means for feeding paper between the rollers, means for intermittently preventing a feeding operation, and means cooperating with said last mentioned means for oscillating said cams.

4. In a machine for cutting blanks including two superposed rollers having cooperating annular cutting edges thereon, a cam on each end of one of said rollers the cams having extensions adapted when in one position to abut against the other roller to separate the two rollers said cams being mounted for rotation independent of the roller upon which they are mounted, means including a shaft spaced from said rollers and having a connecting rod in the nature of a crank driven thereby and secured to one of said cams for providing oscillatory motion for said cam.
